United States Patent Office.

M. B. GOODELL, OF WORCESTER, MASSACHUSETTS.

Letters Patent No. 88,158, dated March 23, 1869.

IMPROVED FOLDING BEDSTEAD.

The Schedule referred to in these Letters Patent and making part of the same.

Know all men by these presents:

That I, M. B. GOODELL, of the city and county of Worcester, and Commonwealth of Massachusetts, have invented certain new and useful Improvements in Folding Bedsteads; and I do hereby declare that the following is a full, clear, and exact description of the same, reference being had to the accompanying drawings, forming a part of this specification, in which—

Figure 1 represents a perspective view of my improved folding bedstead when closed;

Figure 2 represents a section of the same on line A B, fig. 1;

Figure 3 represents a plan view of my folding bedstead when opened; and

Figure 4 represents a longitudinal section of the same on line C D, fig. 3.

To enable those skilled in the art to which my invention belongs, to make and use the same, I will describe it more in detail.

By reference to fig. 1 of the drawings, it will be seen that in this instance, my improved folding bedstead is made, when closed, or folded up, to resemble a bureau. The top, A, ends B, and back C, are secured firmly together, and form a case, or receptacle, into which the frame or bed-bottom and bedding are folded.

A movable front, D, is arranged to fit between the ends B of the case, and furnished with side-pieces E, by means of which it is supported in an upright position, while, at the same time, it can be conveniently drawn out from or moved up to the other parts of the case, for the purpose of folding or unfolding the bed-frame and bedding.

The outside of the movable frame D is finished with knobs and panels, in imitation of the front of drawers, and the ends B are made with suitable panels and scrolls, to resemble a bureau.

To the inner side of each end-piece B, are secured two parallel horizontal strips, F, of wood or metal, between which are fitted sliding blocks, or pieces d, from which project pins, or pivots a, which extend through slots I, formed in the side-rails G, and thereby support one end of the bed-frame, or bottom, while the other end of the bed-frame, or bottom, is supported by pins, or pivots b, that pass through holes in the side-rails G, said pins, or pivots being supported in the side-pieces E, as indicated in the drawings.

The sliding blocks d are made with dovetailed edges, to fit the corresponding edges of the pieces F, whereby said sliding pieces are retained in place.

The rails G are made in two pieces, and are connected in the centre by hinges m, at their under sides, whereby the two parts may be folded together, as shown in fig. 2.

Slats K are arranged across the bottom, upon which may be placed coiled springs, for supporting the bedding, or, if preferred, sacking-cords, or any other materials or device, may be used for that purpose.

The ends of slats K, are fitted in recesses cut in the

longitudinal bottom-pieces O, fastened to the lower inner edges of the side-rails G.

The pieces O also form convenient and proper means for holding the hinges m in place, said hinges being fastened to the side-rails G, and to the pieces O.

Secured to the rails G, by the loops n, is an elastic cord, 4, which may be drawn over the top of the bedding, and fastened to the hook c, for the purpose of preventing any portion of the bedding from being displaced when folding or unfolding the bedstead.

A frame, M, containing drawers N, is, in the present instance, arranged upon the top, A, of the case, but, if preferred, it may be left plain, or be surmounted with a mirror, stand, book-case, or any other article.

To open, or unfold the bedstead, the front piece D is drawn or moved outward, thereby permitting the bed-frame, or bottom to unfold, or assume a horizontal position, after which the bed can be drawn still further out from under the top part A of the case, as shown in figs. 3 and 4, if desired.

When the bed is in this position, the slide-pieces d are drawn to the forward ends of the pieces F, while the pins a rest in the rear ends of the slots f.

Screws, or stops p, are to be used to prevent slide-pieces d from moving too far forward.

To close, or fold up the bedstead, the front piece D is moved inward, until the rear end of the bed-bottom reaches the back, C, of the receptacle, or ease, when, by pressing down on foot-board P, the central, or hinged ends of the bed-bottom are raised, so as to elevate the joints, or hinges m, above the pins a and b, after which, if the part D is forced, or moved back to the forward part of the case, the two parts of the bed-frame, or bottom will be folded together, into a vertical position on the pivots a and b, as indicated in fig. 2.

If desired, the case and movable front D may be mounted on casters, or rolls.

In lieu of finishing the bedstead in imitation of a bureau, it may be finished in the form of a sideboard or book-case, or in any other manner to suit taste or convenience.

A head-board may be arranged across the head of the bed, connected thereto by hinges, so that when the bed is folded, the head-board will be folded down on to the pillows, and when the bedstead is opened, the head-board will be raised, as indicated in the drawings by blue lines, figs. 2 and 4.

One or more swinging supports, or legs may be hinged to the under side of the rails G, or pieces O, so that they will drop to a perpendicular position as the bedstead is opened, or unfolded, and thereby form a support for the central part thereof, to prevent too much strain on the hinges m. (See blue lines, fig. 4.)

It will be observed that the pivots b are so arranged as to admit the foot of the bed frame, foot-board, and foot of the bed to turn down back of the pivots b, and front of the piece D, while the pivots a occupy

such positions as to admit the front part of the bed to turn down between the same and the back, C, of the case. (See fig. 2, of the drawings.)

Having described my improved folding bedstead,

What I claim therein as new and of my invention, and desire to secure by Letters Patent, is—

The combination and arrangement, with a stationary case and its movable front, of a sliding and unfold-

ing bed-frame, the two parts of which are pivoted to and connected with said case and movable front, respectively, substantially in the manner and for the purposes set forth.

M. B. GOODELL.
